UNITED STATES PATENT OFFICE.

GEORGE A. WAY, OF MIDDLEVILLE, MICHIGAN.

FIRE-BACK FOR STOVES.

SPECIFICATION forming part of Letters Patent No. 278,840, dated June 5, 1883.

Application filed January 31, 1883. (No model.)

To all whom it may concern:

Be it known that I, GEORGE A. WAY, of Middleville, in the county of Barry and State of Michigan, have invented new and useful 5 Improvements in Adjustable Fire-Backs; and I do hereby declare that the following is a full, clear, and exact description thereof, reference being had to the accompanying drawings, which form a part of this specification.

10 This invention relates to certain new and useful improvements in the construction of the article known as a "fire-back," such as are to be found employed in cooking stoves and ranges, by means of which one size only need 15 be made, which is readily and easily adjusted to the different sizes of such stoves or ranges.

The invention consists in the peculiar construction of the device by means of which this adjustability is secured.

20 Figure 1 shows a front elevation of my improved fire-back. Fig. 2 is a rear elevation of the same, showing the extension at each end and the adjustability to different sizes of stoves and ranges. Fig. 3 is a detail, showing the recess and vertical breaking-grooves. Fig. 4 is a section through the line $x-x$, Fig. 2.

In the accompanying drawings, which form a part of this specification, A represents a 25 cast-iron fire-back, which is designed to fit a small fire-box of a stove, and, so far as the front is concerned, is of the usual construction and appearance. Upon the rear side are cast two pairs of lugs, a b, the former pair being on a lower plane than the latter, whereby the 30 tongues C and E, hereinafter described, will pass each other without interfering when the fire-back is fitted to a narrow stove.

B represents a slide or a plate provided with a tongue, C, of a slightly dovetail form in 35 cross-section, which engages with the lugs a, so that said plate may be extended or retracted, as may be desired. D represents another similar plate with a similar tongue, E, which engages with the other pair of lugs, b. By 40 forming the lugs upon the back of the plate so as to form a dovetail recess outside of the body of the plate itself, the latter is not weakened thereby, as would be the case were the dovetail recess formed in the body of the 45 plate. These plates, it will be seen, can be readily extended to the right and left, thereby increasing the length of the fire-back to fit fire-boxes of different lengths. It will be seen that the plates B D are provided with recesses

55 e to receive the lugs on the back of the fire-back A, whereby the range of the movement of the plates is much increased. In making such extensions they should be equal at each end, in order to keep the fire-back proper as near the center of the fire-box as possible, for 60 at that point will always be found the hottest fire.

It will be noticed that upon the rear side of the fire-back A and of both the extension-plates grooves c are cast. These are for the 65 purpose of enabling the fitter to break off one or more sections to adapt the device to fire-boxes of differing depths. In the center of the top edge of the fire-back A a recess, f, is formed to receive a thin projection on the 70 back of the fire-box found in some stoves. The front of the fire-back is also provided with vertical grooves d d, corresponding with the sides of the recess f, adapting the section F to be broken out when the projection on the 75 back of the fire-box is too thick to be properly received by the recess f. By this construction it will readily be seen that this improved fire-back will become an immediate article of commerce, as it will enable a party to 80 buy such a device, which he can readily fit into his stove without the necessity of skilled labor so to do.

I am aware of Patents Nos. 172,192, 221,513, 222,183, 159,350, and 211,192, and make no 85 claim to the construction shown therein.

What I claim as my invention is—

1. The center piece, A, provided with longitudinal lugs constructed to form a dovetail recess wholly outside the main body of said 90 center piece, in combination with a side piece having a dovetail-shaped tongue to fit into said recess, having one of its surfaces in line with the portion of said side piece that comes in contact with the back of the center piece. 95

2. The center piece, A, provided with longitudinal lugs a a and b b, constructed to form dovetail recesses outside the main body of the center piece and arranged on different horizontal planes, in combination with two side 100 pieces, B and D, having dovetail-shaped tongues C E, adapted to fit said dovetailed recesses, all constructed, arranged, and operating substantially as shown and described.

GEORGE A. WAY.
